(57) **CLAIM**

We claim the ornamental design for a housing for ball bearings, as shown and described.

DESCRIPTION

FIG. 1 is an isometric top, right view of a housing for ball bearings;

FIG. 2 is a right side elevation view thereof;

FIG. 3 is a front view thereof;

FIG. 4 is an isometric top right side section view thereof, wherein the view is taken along section line 4-4 of FIG. 3; and,

FIG. 5 is a right side section view thereof, wherein the view is taken along section line 4-4 of FIG. 3.

The broken lines depict portions of the article that form no part of the claimed design.

1 Claim, 5 Drawing Sheets---
